UNITED STATES PATENT OFFICE.

SAMUEL S. GILBERT, OF SOUTH WEYMOUTH, MASSACHUSETTS.

TOY HOUSE.

1,302,785.

Specification of Letters Patent.

Patented May 6, 1919.

Application filed January 19, 1918. Serial No. 212,552.

To all whom it may concern:

Be it known that I, SAMUEL S. GILBERT, citizen of the United States of America, and resident of South Weymouth, in the county 5 of Norfolk and State of Massachusetts, have invented new and useful Improvements in Toy Houses, of which the following is a specification.

This invention relates to toys and more 10 particularly to toy building structures of the character adapted to be readily assembled and disassembled without the use of tools.

The objects of the invention are to provide a structure which may be quickly and easily assembled without the use of bolts, screws or the like, which therefore comprises a minimum number of parts and no small parts, which is strong and substantial when assembled, which can be rapidly disassembled, which can be packed or stored in a small space when disassembled, which can be manufactured at small cost and which possesses other advantages for use in the toy art.

25 The invention is illustrated as embodied in a toy house in the accompanying drawings in which,

Figure 1 is a top plan view of the base of the house;

30 Fig. 2 is a section of the base on line 2—2 of Fig. 1;

Fig. 3 is a perspective view of three wall sections;

35 Fig. 4 is a perspective view of the base showing some of the wall sections in position;

Figs. 5, 6, and 7 are perspective views of three forms of clip employed in the construction.

40 Fig. 8 is a perspective view of the base and wall sections of the house assembled together; and

Fig. 9 is a vertical central section of the 45 completely assembled house, the section being taken in the plane of line 8—8 of Fig. 8.

The particular embodiment of the invention shown for the purpose of illustration comprises a base B formed of two parts b and b', wall sections W₁, W₂, W₃, etc., clips 50 C₁, C₂, C₃, etc., roof sections R₁, R₂, R₃, etc., and a roof center piece R.

The base B is octagonal in outline and may be formed of wood, paper-board or other suitable material. The two parts of 55 the base b and b' are joined together by means of hinges h and h', so that they may

be folded together when disassembled from the wall sections. The upper face of the base B is provided with a plurality of grooves G₁, G₂, G₃, etc., to receive the lower 60 ends of the wall sections W₁, W₂, W₃, etc. These grooves have the same cross sectional shape as the lower ends of the wall sections and this shape is preferably rectangular as illustrated in the drawings.

The wall sections are preferably somewhat thinner than the base, as shown, and may be formed of the same or other suitable material. While the shape of the wall sections may be varied to suit various plans of construction they are preferably confined to three general shapes shown in Fig. 3, viz., first, rectangular and full wall height such as W₁, second, inverted L and of full wall height as W₂ and, third, rectangular and less than full wall height such as W₃. The full height rectangular sections W₁ are employed to form a solid wall, whether exterior or interior, and vary in width to suit conditions of space; the inverted L sections 70 W₂ are employed to form doorways or windows, two of the sections preferably being employed together with the bases of the L sections juxtaposed; and the low rectangular sections W₃ are employed in the formation of the windows, these sections being adapted to fill the spaces between the windows and the floor. In addition to these three wall section shapes other more or less ornate shapes may be employed. In Figs. 85 8 and 9, for example, two sections W₄ and W₅ are employed respectively to form the opposite sides of a large interior doorway.

The clips C₁, C₂, C₃, etc., shown in Figs. 5, 6, and 7, are fitted over the upper edges of 95 the wall sections as illustrated in Fig. 8 to assist in holding the wall sections firmly in position. The straight clips C₁ are employed along a straight wall and are so positioned as to extend across the joints in 100 the wall. For the purpose of strengthening the walls it is sufficient to extend the clips only short distances along the wall on opposite sides of the respective joints but in order to make a finished appearance and 105 incidentally to make the structure still more rigid the clips are extended into contact with each other. The angle clips C₂ are employed where two walls meet at an angle and the Y clips C₃ are employed where 110 three walls meet obliquely. Where two walls meet at right angles a T-shaped clip

C_4 is employed as illustrated in Fig. 8. The clips C_1 , C_2 , C_3 , etc., are preferably formed of a stiff material such as steel which will not be readily deformed by ordinary usage.

- 5 The roof sections R_1 , R_2 , R_3 , etc., are substantially triangular in outline and may be formed of the same material as the wall sections. The tip piece R is pyramidal in shape and is provided with recesses around 10 the edge of its base to receive the upper ends of the roof sections R_1 , R_2 , R_3 , etc. Lugs l are provided on the inner sides of the roof pieces near their lower ends to engage the top of the walls and assist in maintaining 15 the roof in position. Similar lugs l' may be provided to engage the base of the pyramidal piece R .

While I have specifically described my invention as embodied in a single physical 20 structure it is to be understood that I desire to protect the novel features of the invention when applied to any building structure irrespective of its shape or plan.

What I claim is:

- 25 1. A toy structure comprising a base having a marginal groove, a plurality of grooves extending in different directions within the space delimited by said marginal groove and a superstructure fitting into the grooves.
2. A toy structure comprising a base having grooves in its upper face and a superstructure detachably associated with the base, said base being made in sections of substantially equal area and jointed so as to be folded together when dissociated from the superstructure.
3. A toy structure comprising a base having a marginal groove in its upper face, 40 a plurality of grooves extending in different directions within the space delimited by said marginal groove and a plurality of wall sections adapted to be mounted in said grooves in juxtaposition to form a continuous marginal wall with a plurality of partition walls inclosed therein.
4. A toy structure comprising a base having a marginal groove in its upper face, a plurality of grooves extending in different 45 directions within the space delimited by said marginal groove, a plurality of wall sections adapted to be mounted in said grooves in juxtaposition to form a continuous marginal wall with a plurality of partition walls inclosed therein, and means for detachably connecting the adjacent wall sections.
5. A toy structure comprising a base having grooves in its upper face, a plurality of 60 wall sections adapted to be mounted in said grooves in juxtaposition, and clips fitting over the upper edges of adjacent wall sections.
6. A toy structure comprising a base having 65 grooves in its upper face, a plurality

of wall sections adapted to be mounted in said grooves in juxtaposed angular relationship and clips fitting over the edges of the sections to hold them together.

7. A toy structure comprising three sections fitting together in angular relationship and a clip having three branches adapted to fit over the edges of the three sections so as to hold the sections together. 70

8. A toy structure comprising a base having a groove in its upper face, and a plurality of wall sections adapted to be mounted in said groove so as to form a continuous wall, one of the sections having an overhanging portion adapted to extend into juxtaposition with the next adjacent section so as to form a window or doorway thereunder. 80

9. A toy structure comprising a base having a groove in its upper face, and a plurality of wall sections adapted to be mounted in said groove so as to form a continuous wall, one of the wall sections having the shape of an inverted L so as to form a window or doorway under the base of the L. 85

10. A toy structure comprising a plurality of 90 triangular sections adapted to be fitted together in pyramidal form, and a tip piece having recesses to receive the tip ends of the sections.

11. A toy structure comprising a base having a marginal groove in its upper face, a plurality of wall sections adapted to be mounted in said groove in juxtaposition to form a marginal wall, and said base having a plurality of grooves in its upper face extending in different directions within the space delimited by said marginal groove, a plurality of wall sections adapted to be mounted in said last named grooves in juxtaposition to form partition walls, means for detachably connecting said last named wall sections together and means for detachably connecting said marginal wall with adjacent partition walls. 100

12. A toy structure comprising a base having a marginal groove in its upper face, a plurality of grooves extending in different directions within the space delimited by said marginal groove, a plurality of wall sections adapted to be mounted in said grooves in juxtaposition to form a continuous marginal wall with a plurality of partition walls inclosed therein and a plurality of roof sections fitted together and adapted to rest on said marginal wall. 105

13. A toy structure comprising a base having a marginal groove in its upper face and a plurality of grooves extending in different directions within the space delimited by said marginal groove, a plurality of wall sections adapted to be mounted in said grooves in juxtaposition to form a continuous marginal wall with a plurality of partition walls inclosed therein, a plurality of triangular roof sections adapted to be fitted 120

125

130

together in pyramidal form and a tip piece having recesses to receive the tip ends of the roof sections.

14. A toy structure comprising a foldable base made in sections of substantially equal area provided upon its upper face with a marginal groove and a plurality of grooves extending in different directions within the space delimited by said marginal groove, a plurality of wall sections adapted to be mounted in said grooves in juxtaposition to

form a continuous marginal wall with a plurality of partition walls inclosed therein, clips adapted to fit over the upper edges of adjacent wall sections to hold them together 15 and a plurality of roof sections fitted together and adapted to rest upon said marginal wall.

Signed by me at Boston, Massachusetts, this 16th day of January, 1918.

SAMUEL S. GILBERT.
